INTERNAL COMBUSTION ENGINE

Norton W. Kinney, Groveland, Mass.

Application April 25, 1935, Serial No. 18,180

4 Claims. (Cl. 123—14)

This invention relates to rotary, or turbine, internal combustion engines and it has for its object to improve the construction and operation of engines of this class.

To these ends I have provided an improved internal combustion engine having the peculiar features of construction and operation set forth in the following description, the several novel features of the invention being separately pointed out and defined in the claims at the close thereof.

In the accompanying drawings:—

Figure 1 is a central longitudinal sectional view of an internal combustion engine constructed in accordance with this invention, the plane of the section being on line 1—1 of Fig. 2.

Figure 2 is a section on line 2—2 of Fig. 1.

Figure 2a is a fragmentary sectional view of one of the compression eccentrics hereinafter referred to.

Figure 3 is a sectional detail hereinafter referred to.

Figure 4 is a section on line 4—4 of Fig. 1.

Figure 5 is a section on line 5—5 of Fig. 2.

Figure 6 is a section on line 6—6 of Fig. 2.

Figure 7 is a diagrammatic end view of the four eccentric portions of the rotor hereinafter referred to and illustrating their angular relationship.

The illustrated embodiment of my invention comprises an interiorly cylindrical casing 10 which may be constructed, as shown, to provide a water jacket 11 and which may be provided at its opposite ends with apertured heads 12, 12 having base portions 12a adapted to be secured in position upon a suitable support.

Within the casing 10 is a tubular rotor member which is indicated generally at 13 in Fig. 1 of the drawings and this rotor member is constructed with hubs 14 fixed in position upon a shaft 15 journaled in bearings provided in the heads 12. This shaft 15 carries a flywheel 29. The hubs 14 are connected with the outer tubular portion of the rotor by radial arms 16 which serve as fan blades to cause a flow of air through the tubular rotor member 13, said air entering the apertures 17 provided through the head 12 at one end of the casing and being discharged through the apertures 18 provided through the head 12 at the opposite end of the casing. Thus while the engine is in operation the rotor 13 is cooled interiorly by a draft of air flowing therethrough and exteriorly by the water jacket 11 of the casing.

The rotor 13 is constructed so that it is composed of a plurality of sections the peripheries of some of which are eccentric with respect to the

axis of the rotor while the peripheries of other sections are concentric with respect to the axis of said rotor. As herein shown there are two pairs of eccentric sections 19 and 20 and 19a and 20a and five cylindrical concentric sections 21, 22, 23, 24 and 25, the concentric cylindrical section 22 fitting the cylindrical interior of the casing and being disposed between the pair of eccentric sections 19 and 20 and the cylindrical concentric section 24 also fitting the cylindrical interior of the casing and being disposed between the sections 19a and 20a.

The two cylindrical sections 21 and 22 provide between them a combustion and expansion chamber 25 within which is disposed the motor eccentric 20; the two cylindrical sections 22 and 23 provide between them a compression chamber 26 which is occupied by the gas compressing eccentric 19; the two cylindrical sections 23 and 24 provide between them another compression chamber 27 within which is disposed the gas compressing eccentric 19a, while the two cylindrical sections 24 and 25 provide between them a combustion and expansion chamber 28 within which the motor eccentric 20a is disposed.

Figure 7 illustrates the angular relationship existing between the sections 19, 19a, 20 and 20a.

Referring to this figure of the drawings, the radial line W bisects the portion of greatest radius of section 20; the radial line Y bisects the portion of greatest radius of the section 20a; the radial line X indicates the portion of greatest radius of the section 19, and the radial line Z indicates the portion of greatest radius of the section 19a.

As shown in Fig. 6 the casing 10 is constructed with two radial slots 30 and 30a communicating at their inner ends, respectively, with compression chamber 26 and compression chamber 27. Within the slot 30 is slidably mounted a gate or partition member 31 whose inner end is equipped with a rocker shoe 32 bearing continuously against the periphery of eccentric 19. Within the slot 30a is slidably mounted a similar gate or partition member 33 whose inner end is likewise equipped with a rocker shoe 34 bearing continuously against the periphery of the eccentric 19a.

The peripheries of the eccentrics 19 and 19a are truly circular and said eccentrics are relatively disposed angularly one hundred and eighty degrees apart so that the gates 31 and 33 must move correspondingly but in opposite directions as the eccentrics are rotated in order to maintain continuous contact with said eccentrics.

Upon its exterior the casing 10 is made with a pair of parallel spaced apart lugs 34', Figs. 2 and 6, supporting the opposite ends of a pivot pintle 35 on which is swivelly mounted a fulcrum block 36 occupying a position within a slot 37 formed in a walking-beam lever 38. At its opposite ends the lever carries rolls 39 and 40, the former abutting the outer end of gate partition 31 and the latter abutting the outer end of gate partition 33. 5

10 A stiff spring 41 occupies a position within slot 37 and between block 36 and the inner end of said slot. This spring is installed under initial compression and serves to yieldingly urge the lever 38 toward the gate partitions 31 and 33 so 15 that the rolls 39 and 40 are maintained continuously in contact with said gate partitions. Thus as each gate partition is shoved outwardly by its eccentric it acts through the walking-beam lever 38 to shove the other gate partition inwardly 20 as the eccentric of the latter recedes, the spring 41 maintaining both gate partitions always in contact with their eccentrics.

The compression chambers 26 and 27 are provided, respectively, with gas inlet ports 42 and 43 25 each disposed at the rear of its gate partition and in close proximity thereto. Therefore, while either eccentric is rotating in the direction indicated by the arrow in Figs. 2 and 4 it co-operates with its gate partition to draw gas into the 30 casing at one side of said gate partition while at the same time, it compresses a charge of gas at the opposite side of said gate partition which was drawn into the casing during the preceding revolution of the eccentric.

35 The concentric cylindrical section 22 of the rotor serves the double function of a partition normally separating the compression chamber 26 from the combustion chamber 25 and also as a valve controlling communication between said two chambers, and the concentric cylindrical section 24 is likewise co-operatively associated with the compression chamber 27 and combustion chamber 28. The concentric cylindrical section 23 of the rotor serves only as a partition separating chamber 26 from chamber 27. The concentric cylindrical end sections 21 and 25 serve only as 40 side walls for the combustion chambers.

The peripheries of the eccentrics 20 and 20a 45 are not truly circular and these two eccentrics are relatively disposed angularly 180 degrees apart and each is disposed relatively to its compression eccentric 19 or 19a 90 degrees in advance of the same, as illustrated in Fig. 2 of the drawings. As shown in Figs. 2 and 2a, a portion of the periphery of the eccentric 20 measuring circumferentially about 60 degrees is concentric with the axis of the shaft 15 and of approximately the same radius as the interior of the casing 10. The remaining portion of the periphery of the eccentric 20 measuring circumferentially about 300 degrees is a circular arc that is concentric with a center that is off-set with respect to the axis of the shaft 15. The eccentric 20a is similarly constructed but, as pointed out above, is disposed 180 degrees removed from the eccentric 20. Likewise, it will be clear that the two compression eccentrics 19 and 19a are positioned relatively 180 degrees apart and each 90 degrees to the rear of its eccentric 20 or 20a.

70 As will be clear from Figs. 2 and 5, the casing 10 is constructed with two radial slots 43 and 43a communicating at their inner ends, respectively, with expansion chamber 25 and expansion chamber 28. Within the slot 43 is slidably mounted a 75 gate or partition member 44 whose inner end is

equipped with a rocker shoe 45 bearing continuously against the periphery of eccentric 20. Within the slot 43a is slidably mounted a similar gate or partition member 46 whose inner end is likewise equipped with a rocker shoe 47 bearing continuously against the periphery of the eccentric 20a.

Since the expansion eccentrics 20 and 20a are relatively disposed angularly 180 degrees apart while the two gate partitions 44 and 46 are aligned longitudinally relatively to the shaft 15, said two gate partitions must move correspondingly and in unison but in opposite directions as the expansion eccentrics are rotated and when the engine is in operation such is the case.

Upon its exterior the casing 10 is made with a pair of parallel spaced apart lugs 48, Figs. 2 and 5, supporting the opposite ends of a pivot pintle 49 on which is swivelly mounted a fulcrum block 50 occupying a position within a slot 51 formed in a walking-beam lever 52. At its opposite ends the lever 52 carries rolls 53 and 54, the former abutting the outer end of gate partition 44 and the latter abutting the outer end of gate partition 46.

20 A stiff spring 55 occupies a position within the slot 51 between block 50 and the inner end of said slot and this spring is installed under initial compression and serves to yieldingly urge the lever 52 toward the gate partitions 44 and 46 so that 25 the rolls 53 and 54 are maintained continuously in contact with said gate partitions. Thus, as each gate partition is shoved outwardly by its eccentric 20 or 20a it acts through the walking-beam lever 52 to shove the other gate partition inwardly as the eccentric of the latter recedes, the spring 55 maintaining both gate partitions always in contact with their eccentrics.

The expansion chambers 25 and 28 are provided, respectively, with exhaust ports 56 and 57, Figs. 2 and 1, each disposed in front of its gate partition and in close proximity thereto. Therefore, while either eccentric 20 or 20a is rotating in the direction indicated by the arrow in Fig. 2, it cooperates with its gate partition to expell the spent gases of the preceding revolution thereof through the exhaust port of its chamber during which time a fresh charge of gas is supplied to the expansion chamber, or rather to a pocket or extension of said expansion chamber forming part of the latter, said pocket or extension being disposed in close proximity to, and at the rear of, its gate partition 44 or 46. In Fig. 2 the pocket or extension of expansion chamber 25 is shown at 58 while the corresponding pocket or extension of chamber 28 is indicated in Fig. 1 by dotted lines at 59.

The casing 10 is made with an approximately radial port 60 communicating at its inner end with the pocket or extension 58 of chamber 25 and into this port is screwed a spark plug 61 as shown in Fig. 2.

The extension 59 of chamber 28 is likewise provided with a spark plug 61.

Upon its interior the casing 10 is formed with a longitudinal groove or channel 62 communicating at its one end with the pocket or extension 58 of chamber 25, said channel or groove 62 extending longitudinally part way across the periphery of the circular section 22 of the rotor. This circular section 22 of the rotor is made upon its periphery with a longitudinal channel or groove 63 which communicates at its one end with the chamber 26 of the compression eccentric 19. It will thus be clear that the two channels or grooves 62 and 63 bear overlapping relationship relative- 75

ly so that once during each revolution of the rotor 13 the channel or groove 63 registers with the channel or groove 62 formed in the casing. The casing 10 is also formed upon its interior with another longitudinal channel or groove 62a that is disposed opposite the periphery of the partition section 24 of the rotor and communicates at its one end with the pocket or extension 59 of expansion chamber 28. Also, the partition section 24 of the rotor is made upon its periphery with a longitudinal channel or groove 63a which communicates at its one end with the compression chamber 27 and which bears overlapping relationship with the channel or groove 62a so that once during each revolution of rotor 13 the channel or groove 63a registers with the channel or groove 62a.

As the portion of compression eccentric 19 that is of greatest radius approaches its gate partition 31 (just back of its position as illustrated by dotted lines in Fig. 2), the channel 63 comes into register with the channel 62 with the result that the compressed gas within chamber 26 between said portion of greatest radius 25 and the gate partition 31 discharges from chamber 26 through channels 63 and 62 into the pocket or extension 58 of chamber 25. This delivery of compressed gas into the pocket or extension 58 occurs, or is initiated, just before the portion of greatest radius of eccentric 20 completely closes the pocket or extension 58 with the result that the first effect of the entering fresh gas is to scavenge said pocket or extension and immediately thereafter communication between pocket or extension 58 and chamber 25 is shut off by said portion of greatest radius.

Immediately after the channel 63 has passed the channel 62 the spark plug 61 is operated to ignite the charge within the pocket or extension 58. Fig. 2 shows the relation of the parts at the moment that the spark plug 61 is thus operated.

When the charge within the pocket or extension 58 is thus ignited it is confined within a space 45 defined by the casing 10, gate partition 44 and the portion of eccentric 20 that is of greatest radius with the result that said eccentric is forced to turn in the direction of the arrow, and since the exhaust of this ignited charge does not 50 start until said portion of greatest radius has passed the exhaust port 56, it will be clear that during the greater portion of the revolution of eccentric 20 the gas is acting expansively upon the said eccentric.

The eccentrics 19a and 20a together with the partition section 24 jointly co-operate in a similar fashion but the power stroke of eccentric 20a occurs 180 degrees after the power stroke of eccentric 20. It will thus be clear that there are 60 two power strokes during each revolution of rotor 13 timed 180 degrees apart.

As will be clear, each gate partition of each pair is positively moved outwardly by its eccentric during one-half of the revolution of the 65 rotor and during the other half of the revolution of rotor 13 the other eccentric of that pair acts through the walking-beam associated with said pair to yieldingly force said gate partition inwardly and maintain it in contact with its eccentric.

Figure 3 is a sectional detail illustrating the construction of the gate partition 31. As shown in this figure, the inner end of the gate partition 31 is formed with a socket 64 within which is mounted to rock a rocker shoe 32, said shoe being held

within said socket by means of the head of a screw 65 whose shank extends through an arcuate slot 66 formed through the rocker shoe 32. This screw 65 and the slot 66 may be disposed midway between the opposite ends of the rocker shoe. 65 The other rocker shoes 34, 45 and 47 are constructed and applied to their gate partitions in a similar manner.

Each concentric partition section 22, 23 and 24 of the rotor is formed upon its periphery with two 10 circular grooves in each of which is mounted a packing ring 67 similar to a piston ring in that it may be split and press yieldingly against the interior of the casing. These packing rings serve to prevent leakage from one chamber to the next 15 chamber or chambers. Similar packing rings 68 may be provided in grooves formed upon the peripheries of the end sections 25 of the rotor.

In practice I may, and preferably do, provide joint-closing packing devices for the gate partitions 31, 33, 44 and 46 and in other places where desired.

At the moment that the channel 63 passes beyond the casing channel 62 a small body of gas will occupy the space between the portion of 25 greatest radius of the compression eccentric 19, and gate 31, Fig. 2, and in order to evacuate this body of gas as said portion of greatest radius approaches the gate partition 31 I form the periphery of the compression eccentric 19 with 30 an arcuate by-pass groove 69 which is shown near the top of Fig. 1 and by dotted lines at the top of piston 18 in Fig. 2, said groove occupying a position opposite the gate partition 31 as said portion of greatest radius moves up to the latter. 35 Therefore, the trapped body of gas referred to is transferred through the by-pass 69 under the gate partition 31 and into the space upon the intake side of gate partition 31.

The compression eccentric 19a is likewise provided with a similar by-pass groove 70, Fig. 1, for the same purpose.

The channels 63 and 63a extend under the adjacent packing rings 67 so that the latter does 45 not interfere with the flow of gas through said channels.

In order to prevent leakage of gas under pressure circumferentially around the partition section 22 either from the channel 62 or from the channel 63 Fig. 1, the said partition section 22 is made upon its periphery with transverse grooves 71a in each of which is mounted a packing strip 71 each of which is yieldingly urged outwardly by a spring 72. The partition section 24 is similarly constructed upon its periphery with packing strips 71 to prevent the passage or leakage of gas under pressure circumferentially from either the channel 62a or the channel 63a. 50

Also, each expansion eccentric 20 and 20a is, as shown in Fig. 2, formed upon the periphery of its portion of greatest radius with a transverse groove or channel 74, Fig. 2a within which is mounted a metal packing strip 73 which is yieldingly held against the interior of the casing at all times by a spring 74 as shown in Fig. 2a. 60 This packing strip 73 occupies a position in front of the ignited and expanding charge during the power stroke of the said eccentric.

The two eccentric sections 19 and 19a are exteriorly cylindrical and their radii of greatest length are disposed 180 degrees apart relatively. The two eccentric sections 20 and 20a have their portions of greatest radius angularly disposed 180 degrees apart and the portion of greatest 75

radius of each is angularly disposed 90 degrees in advance of its complemental eccentric section 19 or 19a. Owing to the cylindrical form of the eccentrics 19 and 19a each contacts with the wall 5 of its chamber 26 or 27 approximately along a line only. On the other hand, each of the eccentrics 20 and 20a is made with the portion of its periphery between the radial lines a and b, Fig. 2a, concentric with the axis of the shaft 15 10 so that each has extended surface contact with the circular wall of its chamber 25 or 28. In the illustrated embodiment of the invention a radial line bisecting the angle a—b, Fig. 2a, of each section 20 and 20a is disposed at right 15 angles with respect to the line of greatest radius of its complemental section 19 or 19a.

What I claim is:

1. A rotary internal combustion engine having, in combination, a casing constructed with 20 inlet and exhaust ports and having a cylindrical interior from end to end thereof; a rotor mounted within said casing comprising three sections including an intermediate partition section having a cylindrical periphery fitting the interior 25 of said casing and dividing said interior so as to provide a compression chamber at one side thereof and an expansion chamber at the opposite side thereof, said periphery being formed with a longitudinal groove extending only part 30 way across the same and communicating at its one end only with said compression chamber, an eccentric gas compressing section fitting within said compression chamber, and an eccentric motor section fitting within said expansion 35 chamber, the interior of said casing being made with a longitudinal groove disposed opposite said partition section and communicating at its one end only with said expansion chamber and disposed relatively to the path of said first mentioned groove so that once during each revolution 40 of said rotor the two grooves register and overlap axially thereby to permit the passage of compressed gas from the compression chamber through said grooves into said expansion chamber; a radially movable abutment gate slidably supported by said casing and continuously engaging the periphery of said gas compressing section; a radially movable abutment gate slidably supported by said casing and continuously engaging the periphery of said motor section, and means for yieldingly holding said gates each in 45 contact with its section.

2. A rotary internal combustion engine constructed in accordance with claim 1 wherein said gas-compressing section is made upon its periphery with a circumferential by-pass through which the compressed gas occupying the space within the compression chamber between said gas compressing section and the gate of said section, after the groove of said intermediate partition section moves out of register with the groove of the casing, is transferred to the intake 5 side of said gas-compressing section. 10

3. A rotary internal combustion engine constructed in accordance with claim 1 and wherein said gas-compressing section is made upon its periphery with a circumferential by-pass, through which the compressed gas remaining within the space within the compression chamber between said gas compressing section and the gate of said section, is transferred to the intake side of said gas-compressing section immediately after the 15 groove of said intermediate partition section moves out of register with the groove of the casing. 20

4. A rotary internal combustion engine having, in combination, a casing constructed with 25 inlet and exhaust ports; a rotor mounted within said casing comprising three sections including an intermediate partition section having a cylindrical periphery fitting the interior of said casing and dividing said interior so as to provide a compression chamber at one side thereof and an expansion chamber at the opposite side thereof, an eccentric gas-compressing section fitting within said compression chamber and an eccentric motor section fitting within said expansion chamber; a movable gate mounted on said casing and continuously engaging the periphery of said gas-compressing section; a movable gate mounted on said casing and continuously engaging the periphery of said motor section, and 30 means for yieldingly holding said gates each in contact with its section, the intermediate partition section of said rotor being provided upon its periphery with a groove which axially overlaps and registers with a groove upon the interior 35 of said casing once during each revolution of said rotor thereby to permit the passage of compressed gas from the space in advance of said gas-compressing section into the space behind the portion of greatest radius of said motor 40 section. 45

NORTON W. KINNEY.
